ASSIGNORS TO REYNOLDS GAS REGULATOR COMPANY, OF ANDERSON, INDIANA, A
CORPORATION OF INDIANA

FLUID-PRESSURE REGULATOR

Application filed October 21, 1927. Serial No. 227,648.

Our invention relates to improvements in pressure regulators and particularly to that type of regulator for maintaining a uniform pressure in gas service pipes irrespective of the fluctuations of pressure in the supply mains.

It is one of the objects of our invention to provide a regulator of the above type wherein the blow-off will be effectually sealed under normal conditions but which will respond readily to abnormal increase in pressure and will maintain the release condition of the regulator until the pressure has been properly restored.

Another object of our invention is to provide a means for effectually seating the intake valve of the regulator. Other objects and advantages will appear more fully hereinafter.

For the purpose of disclosing our invention—

Fig. 1 is a vertical sectional view of a regulator embodying our invention;

Fig. 2 is a perspective view of the blow-off sealing cup;

Fig. 3 is a perspective view of the valve lever mounting device;

Fig. 4 is a sectional view of the intake valve seat, and

Figs. 5 and 6 are sectional views of modifications thereof.

In the structure illustrated the pressure regulator includes a regulator casing having a body portion 1 and a cover 2 detachably connected thereto. A flexible diaphragm 3 is clamped between the body 1 and the cover 2 and is held upwardly by the pressure of the gas on the lower side thereof and against the resistance of a spring 4, the tension of which may be adjusted by a set screw 5.

To the lower side of the diaphragm 3 there is attached one end of a lever 6 pivoted at 7 on a pivot support 8. This pivot support is formed of stamped sheet metal comprising a blank slotted from its opposite ends by parallel slots toward the interior, the slots however, not extending clear to the inner portion of the stamping. There is thus provided a pair of tongues 9—9 which may be turned downwardly at right angles to the

body portion of the support leaving supporting ears 10—10. The supporting ears provide means for clamping the support in position between the top 2 and the body 1 at the narrowed neck portion of the body, the body being notched out at the mounting point of the support to accommodate these ears. The down turned ears 9 provide forks in which the pivot 7 is mounted in suitable openings 11 and between which the lever 6 is positioned. This particular construction of this pivot member has desirable advantages as it permits of a very nice adjustment of the parts and extreme accuracy in assembling without excessive labor in the grinding and finishing of the supports, as has heretofore been the case.

The end of the lever adapted to be attached to the diaphragm is provided on its under face with a notch 12 adapted to receive a cross pin 13 on which this end of the lever rests, between ears 14, depending from the diaphragm plate 15.

The body portion of the regulator is provided with a release opening having an extended tube 16 terminating in a well 17. Enclosing the open end of this tube 16 is a movable mercury well or cup 18, having its bottom convexed as at 19 and provided at its upper end with out-turned ears or lugs 20a, which guide the cup in its vertical movements in the well 17. The cup is normally held with the convexed bottom portion seated against the bottom of the tube 16, which bottom portion is immersed in mercury contained in the cup. By this construction a minimum quantity of mercury for sealing the blow-off opening is required. The bottom 19 substantially closes the open end of the tube 16 and the small quantity of mercury need be only sufficient to seal the junction against leaks.

In event the pressure in the regulator builds up above the desired predetermined point, this pressure acting against the mercury in the tube 16 and the bottom of the cup will force the bottom 19 off its seat permitting the pressure to escape through the tube 16 in a "blow-off". This forces the mercury up in the cup and in some instances it will even overflow the top of the cup. As soon as the

pressure drops as a result of the blow-off, the spring 20 will reseat the cup bottom 19 on the bottom of the tube 16 and the mercury flowing back around the exterior of the tube 5 16 will prevent excessive leakage of the gas pending the resealing of the tube by the placing of the mercury within the tube.

While we have spoken of mercury as the sealing medium, in the cup 18, it will be of 10 course understood that other sealing mediums may be used, such for instance as oil or other liquid.

The end of the lever 6, opposite to that secured to the diaphragm, projects into a reduced lateral extension 21, which forms a valve housing, the top of which has a threaded outlet opening 22. This end of the lever carries a valve 23 rockably supported on a threaded stem 24 by which the valve is adjusted relative to its seat. The valve 23 carries a soft face, preferably in the form of a leather packing or the like 25, which is adapted to engage the valve seat. This seat takes the form of a hollow plug 26 threaded into 20 the wall of the casing 1 and provided with an annular flange 27 seating on the upper face of the wall 1. The upper edge of the plug is provided with an annular groove 28 tapered toward its bottom and forming a 25 pair of concentric knife edge, or substantially knife edge, seats for the leather face 25.

In the structure illustrated in Fig. 5 the double concentric knife edge seat is formed by tapering the upper edge 29 of the seat 35 from a shoulder 30 up, and securing around said shoulder a ring 31 having its upper portion 32 tapered, the two portions thus forming the annular channel 28.

In the structure illustrated in Fig. 6 the ring 31 is seated within the plug instead of surrounding the same, the same effect, however, being obtained.

It should be noted that the lever 6 is formed of stamped sheet metal having the two side 45 flanges 32 thrown down to give rigidity and having the walls of the opening for the pin 24 thrown down as at 35, which gives a surface to form the screw threads for the reception of the threaded pin 24. By the forming 50 of the support 8 and the lever 6 from stamped sheet metal the parts may be made much lighter and much more accurate than has heretofore been the case where such parts have been cast.

We claim as our invention:

1. A pressure regulator, having a blow-off tube, a sealing cup surrounding the open end of said tube and axially movable relatively thereto, a sealing fluid contained within said 60 cup and means for biasing said cup toward a closed position.

2. A pressure regulator having a blow-off tube, a sealing cup surrounding said tube axially movable relatively thereto and having 65 a convex bottom co-operating with the

end of said tube for sealing the same, said cup being adapted to contain a sealing fluid and means for biasing said cup in its closed position.

3. A device of the kind described comprising an inner cup to contain a fluid seal detachably mounted upon the vent outlet or stem of a gas regulator or the like so that said stem projects directly into the fluid seal, and an outer cup concentric with and surrounding and coacting with the inner cup to catch the seal fluid overflowing the upper open end of the inner cup. 70

4. In a device of the kind described, an inner mercury cup, means for temporarily and detachably mounting said inner cup upon the vent outlet or stem of a gas regulator or the like, and an outer cup substantially surrounding and coacting with the inner cup to normally maintain said inner cup in position and catch any mercury overflowing from the inner cup. 75

5. The combination with a gas regulator including a vent outlet or stem, an inner cup removably mounted thereon, a sealing fluid in said inner cup, and an outer cup detachably connected to the regulator and coacting with said inner cup to normally hold the latter in place and to catch any portion of the seal fluid overflowing from said inner cup. 85

6. A pressure regulator having a blow-off tube, a sealing cup surrounding the open end of said tube and axially movable relatively thereto, a sealing fluid contained within said cup, means for urging said cup toward a closed position and an outer cup immovably but detachably connected to the regulator about said movable cup and coacting with the latter to catch any portion of the sealing fluid overflowing from said movable cup. 100

7. A device of the kind described comprising a sealing cup to contain a fluid seal and axially movable upon the vent outlet or stem of a gas regulator or the like so that said stem projects into the fluid seal, and an outer cup immovably but detachably connected to the regulator concentric with and surrounding and coacting with the movable cup to catch the seal fluid overflowing the upper open end of the movable cup. 110

8. A pressure regulator having a blow-off tube, a sealing cup surrounding said tube and axially movable relatively thereto and having a convex bottom cooperating with the end of said tube for sealing the same, said cup being adapted to contain a sealing fluid, spring means normally pressing upwardly against said cup bottom for urging the latter toward a closed position, and an outer cup 125 immovably but detachably connected to the regulator about said movable cup and coacting with the latter to catch any portion of the sealing fluid overflowing from said movable cup. 130

In witness whereof, we have hereunto set
our hands at Anderson, Indiana, this 18th
day of October, A. D. one thousand nine hun-
dred and twenty-seven.
